(57) **CLAIM**

The ornamental design for a taillight for a vehicle, as shown and described.

DESCRIPTION

FIG. 1 is a front elevational view of a first embodiment of a taillight for a vehicle according to the design;
FIG. 2 is a left, front perspective view thereof;
FIG. 3 is a left side view thereof; and
FIG. 4 is a top view thereof.

FIG. 5 is a front elevational view of a second embodiment of the taillight for a vehicle, with the taillight for a vehicle for the opposite side of the vehicle being depicted in the first embodiment;

FIG. 6 is a right, front perspective view thereof;
FIG. 7 is a right side view thereof; and
FIG. 8 is a top view thereof.

FIG. 9 is a front elevational view of a third embodiment of the taillight for a vehicle according to the design;
FIG. 10 is a left, front perspective view thereof;
FIG. 11 is a left side view thereof; and
FIG. 12 is a top view thereof.

FIG. 13 is a front elevational view of a fourth embodiment of the taillight for a vehicle, with the taillight for a vehicle for the opposite side of the vehicle being depicted in the third embodiment.

FIG. 14 is a right, front perspective view thereof;
FIG. 15 is a right side view thereof; and
FIG. 16 is a top view thereof.

The broken lines in the drawings illustrate environmental subject matter only and form no part of the claimed design.
Also enclosed is a set of photographs of an embodiment of the design.
